UNITED STATES PATENT OFFICE.

BRUNO PAUL BOHACEK, OF FRANKFORT-ON-THE-MAIN, GERMANY, ASSIGNOR TO
MASCHINENFABRIK MOENUS AKTIEN-GESELLSCHAFT, OF FRANKFORT-ON-THE-
MAIN, GERMANY.

PEGGING MACHINE.

Application filed April 12, 1926, Serial No. 101,471, and in Germany August 22, 1924.

This invention relates to machines for pegging soles to shoes, and is herein shown as embodied in a machine of the type disclosed in the United States Letters Patent No. 5 581,066. This type of machine has as its principal parts a horn rotatable about a vertical axis and adapted to support a shoe with the sole uppermost in an approximately horizontal plane, an awl for piercing the layers of the sole to be connected by the wood-pegs, a hammer for driving single pegs into the holes, and a device for feeding the shoe after every cycle of operation.

The main object of this invention is to improve the machine of the type above mentioned so as to enable it to drive the pegs in a direction inclined to the direction of the feed of the shoes.

Accordingly, a feature of the invention 20 consists in the arrangement of the awl and hammer obliquely to the direction of the feed of the shoe.

A further feature of this invention is found in the arrangement of the horn which is so constructed as to be able to yield in a direction parallel to the inclination of the awl and hammer.

Another characteristic of this invention is found in the means for guiding the shoe 30 with respect to the awl and hammer so that the driven pegs may be reversely inclined.

These and other features and advantages of the invention, including certain details of construction and combinations of parts, 35 will be fully set forth and explained in the following detailed description of so much of a machine embodying a preferred form of the invention as is necessary for a complete understanding thereof, and will then be 40 clearly defined in the appended claims.

Referring to the drawings:

Fig. 1 is a front elevation partly in section and

Fig. 2 a side elevation of the machine.

Fig. 3 is a front elevation of the machine-head.

Fig. 4 is a side elevation of the machine-head partly in section.

Figs. 5-7 show the guiding roll and its 50 adjusting means in cross-section, in longitudinal section, and in plan respectively.

The standard 1 supports the machine head 2 having mounted therein the rotating driving shaft 66 and the slide 54 laterally movable on the bolts 55, 56 by the cam 57 on

the shaft 66. In the slide 54 there moves at the proper time in a vertical plane the rail 50 to which is fastened by the screw 51 the feed-member 49, the bar 46 with the awl 4 fastened thereto by the clamping plate 47, and the bar 63 with the peg-driver 3 fastened to it by the clamping plate 64. The rail 50 is raised and lowered by the lever 53 coacting with the cam 52. The awl-bar 46 is moved by the cam-operated bell-crank lever 48 journaled with its shaft 68 in the machine head. The pegging bar 63 is lifted by the cam 65 and is driven down in the proper moment by a suitable spring. The awl 4 is guided in the feed-member 49. The feed-member 49 projects into the slot of the pressure-plate 58. This plate is adjustably accommodated in the carrier 59 so as to contact with the work operated upon. The peg-driver 3 is guided in a bore of the member 62 fastened to the slide 54.

As thus far described the machine head is of a well known construction. But as seen from an inspection of the drawings the pegging-tools i. e. the awl 4 and the driver 3, 80 do not move as hitherto in a vertical direction, but in an oblique direction.

The pressure-plate 58 is adapted to cooperate with the tip 60 of the head 61 of the horn 5. The horn 5 is rotatable about a vertical axis. The shank 6 of the horn 5 is accommodated in the sleeve 7 provided with two eyes for the pivot-bolts 8, 9. The bolts 8, 9 are connected by the links 10, 11 with the pivots 12, 13 journaled in the arm 14 screwed to the standard 1. The direction of movement of the pegging-tools 3, 4 is vertical to the links 10, 11, so that the horn can yield in this direction. The hole in the middle of the tip of the horn is therefore in alignment 95 with the direction of the awl or of the driven peg notwithstanding the varying thickness of the work.

The horn is provided with a well-known device for severing the pegs. These means are connected by a ball-joint 70 to the actuating bar 15. The bar 15 is on the other hand connected by a ball-joint 71 and by the parts 20, 19, 18 and 17 to the bell-crank lever 16 journaled in the machine-head and 105 oscillated by the cam 69 of the driving-shaft 66. By these means the severing device is allowed to follow any rotative and sideward movement of the horn. The plate 21 for raising and lowering of the horn is con- 110

nnected by the links 22, 23 and by the vertically movable yoke 24 to the treadle 25.

By depressing the treadle 25 the horn 5 is lowered parallel to the direction of movement of the pegging tools. The same is the case if the horn lowers during the automatic operation of the machine. The points of the pegs to be cut away by the severing device lie therefore always in the middle of the 10 head of the horn and can be easily severed.

The roller 26 for guiding the shoe is rotatably journaled in the lever 27. The lever 27 may be tilted about the horizontal pivot 29 of the slide 28. The rearward end of the 15 lever 27 is constantly pressed down by the spring 38. Its lowest position is determined by the stop plate 31. The slide 28 is movable on the double-slide 30. The end positions of the slide 28 are determined by the dog 20 40 projecting into the slot 41 of the double-slide 30. The guiding roll 26 may be pulled forward or pushed back in respect to the pegging tools. In the former case the shoe worked upon lies behind the roll 26, in the 25 latter case it lies before the roll 26. These two different positions of the roll 26 and of the shoe allow two rows of reversely inclined pegs to be obtained. As soon as one 30 row of pegs is driven, the roll 26 is pressed down to allow its passage underneath the pegging-tools and is moved into its opposite position where the spring 38 brings the roll 26 back into its normal height and the pegging of the second row can be started.

35 Moreover the slide 30 is carried by the plate 32 and may be adjusted relatively thereto by means of the lever 33 rotatable about the pivot 37 and carrying a projection 42 engaging into a notch of the double-slide 30.

40 The positions of the adjusting lever 33 are determined by the notched stops 34, 35 themselves adjustably fixed in the curved slot 43 by the screws 44, 45. The adjusting lever 33 is provided with a locking bolt 36 moved by the spring-pressed handle 39 of the lever 33 and abutting against the stop 34 or the stop 35. By means of the lever 33, the bolt 36 and the stops 34, 35 the distance of the 45 peg-rows from the sole-edge may be adjusted and the number of the peg-rows may be multiplied.

The operation of the machine is as follows:

50 The horn 5 is depressed by the treadle 25 and the shoe to be pegged is placed with the sole uppermost on the head 61 of the horn 5 and with its edge adjacent to the guiding-roll 26. As the treadle is released the horn with the shoe thereon is pressed by the spring 67 against the plate 58. By depressing the treadle 72 the machine is started. The feeding-member 49 lowers and takes hold of the work. The sole is moved out of contact with the plate 58 and the 55 horn is partly depressed. Then the awl

partly penetrates into the work. The member 49 and the awl 4 move to the left (Fig. 3) and effect the feed of the work. After the feed has taken place, the member 49 lifts, and the work is pressed anew against the plate 58 by the horn and its strong spring 67. This pressure prevents the work from becoming in any way displaced. The awl pierces now wholly the work and moves back into its upper position. The pressure-member 49 and all parts connected to the slide 54 then return into their right-hand position (Fig. 3). In this position the driver 3 is exactly in alinement with the pierced hole, so that the peg can be driven home. The pegging and feeding repeats until one row of pegs is finished. Then the treadle 72 is released and the machine stopped in order to adjust the guiding roller 26 for the second row of pegs. After this adjustment the machine is again started to continue the operation just described. The pegs driven into the sole of the shoe which is held in an approximate horizontal plane are directed obliquely to the right or to the left according to the backward or forward position of the guiding roll 26 with respect to the shoe on the horn. If one row of pegs is driven to the right and the other row to the left then the layers of the shoe connected by the pegs 95 cannot any more be disconnected unless the pegs are destroyed.

Having thus described the invention what is claimed is:

1. In a pegging machine, the combination 100 with an awl, a driver, and means for feeding the shoe, of a horn rotatable about an axis in the plane of movement of the awl, driver and the feeding means and at an angle with the direction of the piercing and driving movements of the awl and driver respectively.

2. In a pegging machine, the combination 105 with an awl, a driver, and means for feeding the shoe, of a horn rotatable about an axis in the plane of movement of the awl, driver and the feeding means and at an angle with the direction of the piercing and driving movements of the awl and driver respectively and of means allowing the horn to yield parallel to the direction of the said piercing and driving movements.

3. In a pegging machine, a horn rotatable about an axis vertical to the bottom of a shoe held thereon, an awl and driver arranged to move obliquely to the said bottom, and two 120 parallel connection links between the horn and the machine frame arranged approximately vertical to the oblique direction of movement of the awl and driver.

4. In a pegging machine, an awl, a driver, means for feeding the shoe, a horn rotatable about an axis in the plane of movement of the awl, driver and the feeding means and at an angle with the direction of the piercing and driving movements of the awl and driver 130

- respectively, means within the horn for severing the ends of the driven pegs, means for automatically operating the severing means, and a universal connection between the said 5 operating means and the severing-means allowing the severing-means to move laterally with the horn.
5. In a pegging-machine, a horn rotatable about an axis vertical to the bottom of the 10 shoe held thereon, means for feeding the shoe, means for clamping the shoe between the horn and a stationary plate after the feeding means have released the shoe, and an awl arranged to move obliquely to the 15 shoe-bottom and to penetrate partly into the said bottom before the feed takes place and to pierce fully the said bottom after the feed has been effected and the clamping means have taken hold of the shoe.
20. 6. In a pegging machine, an awl, a driver, means for feeding the shoe, a horn rotatable about an axis in the plane of movement of the awl, driver and the feeding means and at an angle with the direction of the piercing and driving movements of the awl and 25 driver respectively, and means for position-

ing the shoe with respect to the awl and driver so that different rows of pegs of a reverse obliquity may be obtained.

7. In a pegging-machine, the combination 30 with a horn rotatable about an axis vertical to the bottom of the shoe held thereon, an awl and driver arranged to move obliquely to the said bottom, and a guide adapted to position the shoe as a whole before the awl 35 and driver or behind them.

8. In a pegging-machine, the combination 35 with a horn rotatable about an axis vertical to the bottom of the shoe held thereon, of an awl and driver arranged to move obliquely 40 to the said bottom, and a guide-roll for the sole-edge positioned at will alternately before the awl and driver or behind them.

9. In a pegging-machine, the combination 45 with a horn rotatable about an axis vertical to the bottom of the shoe held thereon, of an awl and driver arranged to move obliquely to the said bottom, and a work-guide pivoted on a horizontal shaft and movable transversely to the axis of the horn. 50

In testimony whereof I affix my signature.

BRUNO PAUL BOHACEK.
